DESIGN FOR A TUBULAR LIGHT FIXTURE

Ervin C. Koegel, St. Louis, Mo., assignor to Edwin F. Guth Company, St. Louis, Mo., a corporation of Missouri

Application July 3, 1940, Serial No. 93,402

Term of patent 14 years

To whom it may concern:

Be it known that I, Ervin C. Koegel, a citizen of the United States, residing in the city of St. Louis and State of Missouri, have invented a new, original, and ornamental Design for a Tubular Light Fixture, of which the following is a specification, reference being had to the accompanying drawing, forming part thereof, in which

Fig. 1 is a perspective view of the tubular light fixture as viewed from below, showing my new design;

Fig. 2 is an elevational end view thereof with approximately one-half of the end plate removed in order to show the arrangement of the tubes in the fixture.

I claim:

The ornamental design for a tubular light fixture, substantially as shown.

ERVIN C. KOEGEL.
